United States Patent Office.

JESSE FEWKES, OF NEWTON, MASSACHUSETTS.

Letters Patent No. 71,291, dated November 26, 1867

IMPROVEMENT IN SPOOL-SUPPORTS.

The Schedule referred to in these Letters Patent and making part of the same.

TO ALL WHOM IT MAY CONCERN:

Be it known that I, JESSE FEWKES, of Newton, in the county of Middlesex, and State of Massachusetts, have invented certain Improvements in Spindles for Spools, Bobbins, &c.; of which the following is a full, clear, and exact description, reference being had to the accompanying drawings, making part of this specification, in which—

Figure 1 is a plan.

Figure 2 is a vertical section on the line $z z$ of fig. 1, representing a spool secured in place within its frame upon a vertical spindle.

Figure 3 is vertical section on the line $y y$ of fig. 1, representing the spindle in a position to admit of the removal of the spool.

My invention has for its object, to support a spool, reel, or bobbin upon its spindle, and to provide a means for readily removing it therefrom, and my invention consists in pivoting, within the frame, one end of the spindle, in order that it may be swung to one side to receive the spool, reel, or bobbin, when it is locked in position, by fitting over a pin or projection rising from the opposite side of the frame, or by a projection on the spool, &c., fitting into a hole or socket in the frame.

To enable others skilled in the art to understand and use my invention, I will proceed to describe the manner in which I have carried it out.

In the said drawings, A is a spool-frame, to the inside of the upper end of which, at a , is loosely pivoted a spindle, b , which is free to be swung to either side by hand into the position seen in fig. 3, to allow of the spool B being readily slipped thereon or removed therefrom. From the inside of the lower portion of the frame, rises a pin or projection, c , over which fits the hollow portion of the lower end of the spool, when the spindle is swung back into a vertical position, as seen in fig. 2, the resistance of a spiral spring, d , surrounding the spindle, serving to keep the spool in place upon the projection c , and prevent any liability of rattling or jumping out. e is a guide through which the yarn is led to the weaving point. When it is desired to remove the spool from its frame, it is simply necessary to press it upward (against the spring) until its lower end clears the pin or projection c , when it may be swung to one side, and removed from the spindle. Instead of the spool B fitting over a pin, c , projecting from the frame A, a pin projecting from the spool may fit into an opening in the frame, and the spindle may be horizontal instead of vertical, without departing from the spirit of my invention. I have referred in the foregoing description to a stationary spindle, but may use one which revolves, if circumstances should make it desirable.

Claim.

What I claim as my invention, and desire to secure by Letters Patent, is—

A spindle, b , pivoted loosely within its frame A, in combination with a pin, c , or equivalent device, substantially as and for the purpose set forth.

JESSE FEWKES.
